DESIGN FOR A BOTTLE WASHER

James L. Herold, St. Louis, Mo., assignor to Barry-
Wehmiller Machinery Company, St. Louis, Mo.,
a corporation of Missouri

Application November 16, 1939, Serial No. 88,313

Term of patent 14 years

To all whom it may concern:

Be it known that I, James L. Herold, a citizen of the United States, residing in the city of St. Louis and State of Missouri, have invented a new, original, and ornamental Design for a Bottle Washer, of which the following is a specification, reference being had to the accompanying drawing, forming part thereof.

Fig. 1 is a perspective view of a bottle washer showing my new design.

Fig. 2 is a side view of the side opposite to that shown in Fig. 1.

In Fig. 2 the small rectangular box-like elements at the front of the machine, and the higher circular members on the extended upper front portion are omitted for convenience of illustration.

I claim:

The ornamental design for a bottle washer, substantially as shown.

JAMES L. HEROLD.
